UNITED STATES PATENT OFFICE.

WILLIAM M. CRANE, OF NEW YORK, N. Y.

DESIGN FOR A FRONT MEMBER FOR GAS-STOVES.

SPECIFICATION forming part of Design No. 32,882, dated June 26, 1900.

Application filed March 7, 1900. Serial No. 7,748. Term of patent 7 years.

To all whom it may concern:

Be it known that I, WILLIAM M. CRANE, a citizen of the United States, and a resident of New York city, in the county of New York and State of New York, have invented a certain new and useful Design for a Front Member of a Gas-Stove, of which the following is a specification.

My drawing represents a front elevation of 10 that part of the stove which comprises the design, embracing the front frame, oven-doors, and stove-legs, the parts shown constituting the front member of the stove.

The oven-doors have an outward swell, and 15 their ornamentation and that upon the frame overlap each other, producing the effect of an absence of joints between the parts. The extended leaf ornamentation of the upper door springs from the bottom of the door, sweeps 20 around the ends of the door, and converges centrally toward the semicircular name-plate,

as shown. The lower door has a grill as a central feature, with scroll and leaf ornamentation symmetrically disposed on each side of it, the two sides being similar. The hinges 25 of each of the doors are appropriate extensions of portions of the ornamentations.

The ornamentation of the front or frame gives to it an irregular outline, as shown.

The legs are ornamented in keeping with 30 the rest of the design.

What I claim is—

The design for the front member of a gas-stove substantially as shown.

Signed at Peekskill, in the county of West- 35 chester and State of New York, this 12th day of February, A. D. 1900.

WILLIAM M. CRANE.
